UNITED STATES PATENT OFFICE.

HEINRICH HABLÜTZEL-FREI, OF ZURICH, SWITZERLAND.

TREATING HANKS OF YARN WITH LIQUID.

1,383,300.

Specification of Letters Patent. Patented July 5, 1921.

Application filed February 4, 1921. Serial No. 442,459.

To all whom it may concern:

Be it known that I, HEINRICH HABLÜTZEL-FREI, a citizen of the Republic of Switzerland, residing at Zurich, Switzerland, have 5 invented certain new and useful Improvements in Treating Hanks of Yarn with a Liquid Contained in a Trough; and I do hereby declare the following to be a clear, full, and exact description of the invention, 10 such as will enable others skilled in the art to which it appertains to make and use the same, reference being had to the accompanying drawing, and to letters or figures of reference marked thereon, which form a part 15 of this specification.

This invention relates to improvements in an arrangement for treating hanks or skeins of yarn with a liquid contained in a trough and used, for example, for dyeing or bleaching 20 yarn.

In the arrangement which consists of a frame movable over the dyeing trough and carrying a pair of flexible endless conveying members, for instance chains, each of 25 which passes over two lower and two upper disks, for instance chain-wheels, of which the two upper ones are nearer one another than the lower ones, so that each flexible conveying member has the form of a trapezoid. In this manner inclined slopes for 30 lifting and lowering hank-carriers are provided in an arrangement which has only two flexible conveying members. The latter are provided with double-hooked members for 35 taking up and delivering the hank-carriers.

According to the present invention tongues are provided in front of the inclined slopes by the action of which the hank-carriers are 40 lifted off the slopes and off the double-hooked members and let down at some distance from the descending slopes. In this manner a safe placing of the hank-carriers is attained.

One mode of carrying the invention into 45 effect is shown by way of example in the accompanying drawing in which:

Figure 1 shows the movable frame in a section along line I—I of Fig. 2 and fitted with the tongues according to the invention,

Fig. 2 is a cross-section of Fig. 3, the left hand side of this figure showing a section on the line II—II and the right hand side a section along line II'—II' of Fig. 3,

Fig. 3 is, on a larger scale, a section on the line III—III of Fig. 2 and

Fig. 4 illustrates a section along line IV—IV of Fig. 3.

1 denotes the trough containing the dyeing or bleaching liquid. The girders 2 on 60 both sides of the trough carry rails 3 provided with teeth or serrations 4, a rack 5 and a track 6. A frame or carriage 8 provided with wheels 7 moves along the tracks 6. The toothed racks 5 are engaged by the 65 teeth of gear wheels 9, one of which is shown in the left hand side of Fig. 2, which wheels are rigidly connected with spur wheels 9^a, the latter being in engagement with pinions 16^a. The pinion 16^a is rigidly connected with the chain-wheel 16, driven from the shaft 13 of an electrical motor 14 arranged in the frame 8 by means of a chain-wheel 15 and a chain 17. The revolving shaft 13 causes thus the frame 8 to move 70 along the tracks 6 over the trough 1. Chain wheels 12 are provided rigidly connected with the chain wheels 16 and chain wheels 10 are turnably arranged on the axles supporting the wheels 7 and chains 11 connecting the chain wheels 12 and 10 on each side of the frame. The axes of the four chain wheels 10 are in the same horizontal plane. Also the axes of the four chain wheels 12 are in the same horizontal plane. The chain 80 wheels 12 mounted on the same side of the frame 8 are, when seen from the side (Fig. 1), a little nearer one another than the chain-wheels 10, so that the endless flexible chain 11 forming a conveying member and 85 passing over the chain wheels 10 and 12 on the same side of the frame 8 forms a trapezoid having two inclined sides 11^a and 11^b. The shaft 13 drives the chain wheel 12 by means of chains 17 passing over chain wheels 95 15 and 16. The chains 11 carry hooks 18 arranged one opposite another and provided on one side with a recess 19 and on the opposite side with a recess 20. 21 are hank-carriers of a known construction, which lie 100 normally between the teeth of the rails 4 and on which are suspended the hanks of yarn. Tongues *y* are provided in front of the inclined parts 11^a and 11^b of the chains 11. Each tongue is fixed at its lower end on 105 an axle *y*¹ turnably mounted in frame 8 and is pressed with its upper free end against the chain 11, the pressure being effected by means of a lever *Z* one end of which is fixed on the axle *y*¹, its other end being acted upon 110 by a tension spring *w*.

When the frame is moved in the direction

of the arrow shown in Fig. 1 either by means of the motor 14 or the hand drive 22, the endless chains 11 are moved in the directions of the arrow shown in Fig. 1. Each recess 20 of two opposite members 18 provided with a double-hook takes up a hank-carrier 21 which is conveyed by these members up the slope 11^a and then along the upper horizontal part of the chain 11. On their further movement the ends of the hank-carrier come to bear against the tongues *y* whereby the hank-carrier 21 is lifted off the double hooked members 18 and off the inclined chain 11^b and caused to glide along the tongues into the space 4^a between the teeth 4. Without the provision of these tongues the hank-carrier is let down into the space 4^b. The fact that the hank-carrier is thus placed at some distance from the inclined chains the following double hooked member is prevented from engaging with the hank-carrier. At the opposite slope 11^a up which the hank-carriers are conveyed, the ends of the latter pass between the chains 11 and the tongues *y* whereby the ends of the tongues are somewhat lifted to enable the passing.

I claim:

1. In an arrangement for treating hanks of yarn with a liquid contained in a trough, a frame movable over the trough, a pair of endless flexible conveying members provided with double hooked members and forming inclined slopes for lifting and lowering the hank carriers engaged by said hooked mem-

bers, and means provided in front of said slopes for lifting the hank carriers off the hooked members and the conveying members and for placing them at some distance from the descending slope.

2. In an arrangement for treating hanks of yarn with a liquid contained in a trough, a frame movable over the trough, a pair of endless flexible conveying members provided with double hooked members and forming inclined slopes for lifting and lowering the hank carriers engaged by said hooked members, and tongues provided in front of said slopes co-operating with the conveying members for lifting the hank carriers off the hooked members and the conveying members and for placing them at some distance from the descending slope.

3. In an arrangement for treating hanks of yarn with a liquid contained in a trough, a frame movable over the trough, a pair of endless flexible conveying members provided with double hooked members and forming inclined slopes for lifting and lowering the hank carriers engaged by said hooked members and pivotally mounted spring loaded tongues provided in front of said slopes co-operating with the conveying members for lifting the hank carriers off the hooked members and the conveying members and for placing them at some distance of the descending slope.

In testimony that I claim the foregoing as my invention, I have signed my name.

HEINRICH HABLÜTZEL-FREI.
